UNITED STATES PATENT OFFICE.

DOUIA C. PUTNAM, OF WAYNE CENTRE, NEW YORK.

OSCILLATING ENGINE.

SPECIFICATION forming part of Letters Patent No. 319,423, dated June 2, 1885.

Application filed February 12, 1885. (No model.)

To all whom it may concern:

Be it known that I, DOUIA C. PUTNAM, of Wayne Centre, in the county of Wayne and State of New York, have invented a new and Improved Oscillating Engine, of which the following is a full, clear, and exact description.

The object of my invention is to provide a simple and efficient valve-motion to actuate the valves of oscillating engines and provide for running the engine crank-shaft in opposite directions, and for reversing the motion at will and without the use of eccentrics, commonly employed for the purpose.

The invention consists in certain special features of construction of the valve-motion, and in its connections to the valves and the starting, stopping, and reversing lever, all as hereinafter fully described and claimed.

Reference is to be had to the accompanying drawings, forming part of this specification, in which similar letters of reference indicate corresponding parts in all the figures.

Figure 1 is a sectional side elevation of my improved oscillating engine. Fig. 2 is a transverse sectional elevation, the section being taken through the center of the cylinder and steam-chest. Fig. 3 is a detail sectional plan view of the devices for regulating the movement of the engine-valves. Fig. 4 is a sectional diagram view illustrating the positions of the cylinder, its valves and connections when the piston is at half back-stroke; and Fig. 5 is a diagram view showing the devices for regulating the movement of the engine-valves in the positions they assume on the completion of the back-stroke of the piston.

The letter A indicates the engine bed or frame, and B is the steam-cylinder, which is journaled by opposite hollow trunnions, C D, in suitable pillow-block standards, A', rising from the bed A. A steam-supply pipe, E, is fitted in the bed A, so as to communicate with the interior of the trunnion C, from which a live-steam passage, C', leads up to the live-steam space C² in the steam-chest F, which in the instance shown is arranged on the top of the rocking cylinder B, and an exhaust-steam space, D², in chest F communicates, by a side passage, D', with the hollow trunnion D, which discharges the exhaust-steam into a pipe, G, which may convey said steam to a

feed-water heater or discharge it into the atmosphere. At the opposite ends of the steam-chest F are seated the rocking or rotary valves H I, respectively, and to which steam-ports h i lead from the steam-space C² in the chest F, and the valves H I are cut away at the side, as at h' i', so that in rocking axially they connect the opposite ports, B' B², of the cylinder B with the steam and exhaust spaces C² D² of the steam-chest F. I cut away the surfaces of valves H I at opposite faces alike, as shown in Fig. 1, so that should one acting face of the valves wear out of order the valves may be turned clear around to use their other sides or faces, and thus form practically new valves.

To the stems of valves H I are connected rigidly the arms H' I', which are pivoted at their outer ends to the opposite ends of bar J, to which is connected at k the rod K, which connects with the valve operating and regulating devices, hereinafter described.

The letter L indicates the engine-piston, which connects by its rod L', passing through the cylinder stuffing-box b, with the wrist-pin m of the crank M, fast on the shaft M', to which the fly-wheel or drive-wheel M² is fixed.

To relieve the piston-rod L' from bending strains, I connect the wrist-pin m of crank M to a block, L², which slides in guides L³, which are held firmly to the head of the cylinder B by braces L⁴ L⁴, fixed to opposite ends of the guides, as shown clearly in Fig. 1.

On a pin, a, held to a standard, A², rising from the bed-frame A, is hung loosely the triangularly-shaped plate N, and so one of its angles faces the engine-cylinder B.

Along the sides of the plate N which converge toward the cylinder B are formed the edge flanges, n n', which converge but do not touch near the point or end of the plate, and extend forward to form a guide-slot at n², into which may pass a pin, P, which is fixed to a block, P', which is adapted to slide in a slot, q, of an arm, Q, fixed to the adjacent end of the steam-cylinder B. The rear side or part of the plate N has fixed to or formed on it the slotted bar or link N', which is curved in a radius described from the connecting-pin k of the rod K, the connecting pivot-pin k' of which rod is fast to a block, K', which is fitted to slide in the link N', from one end of the link-

slot to its other end, for reversing the motion of the engine, or may be set at intermediate positions for slower speed in either direction, as hereinafter more fully explained.

5 On the pin a and against the plate N is hung loosely the plate O , the opposite converging edges, $o\ o'$, of which are shaped so that when their meeting point o^2 strikes either side flange, $n\ n'$, at the mouth of the guide-slot n^2 , guide ways or slots $n^3\ n^4$ will alternately be formed between the edges $o\ o'$ of plate O and the next adjacent flanges $n\ n'$ of the plate N , and in which guideways $n^3\ n^4$ the pin P of block P' is adapted to pass from the guide-slot n^2 , as presently explained. A spring, R , connected at one end to an arm, O' , projecting from the back edge of rock-plate O , and connected at its other end to a relatively fixed arm, S , projecting in this instance from the bed A or its standard A^2 , serves to throw the point o^2 of plate O to reverse sides of the guide-slot n^2 , as the pin P enters the slot n^2 from the opposite guideways, $n^3\ n^4$. It will be seen that the pin P primarily causes the shifting of the valves $H\ I$, as it is swung up and down by the oscillation of the engine-cylinder B .

To the block P' of pin P is attached at t one end of a rod, T , which, as shown, is bent downward, to allow the block K' of valve-rocking bar K to be lowered to the bottom of the slot in link N' , and the rod T extends forward and is bent upward to connect at t' with an arm, u , which is rigidly fixed to a short shaft or pin, u' , to which is fixed the starting and stopping lever U , the lower end of which stands about at a right angle with the arm u . The shaft or pin u' is journaled in a post or standard, A^3 , which has a series of notches, a^3 , in its upper part, into the center one of which notches the lever U may be set to stop the engine; or the lever may be set into notches at either side to allow slow or fast speed of the engine in reverse directions.

To control the movements of the valves $H\ I$ by and from the lever U , its lower end is connected pivotally to a link-rod, v , which connects with one arm of an angle-lever, V , pivoted at a^4 to a standard, A^4 , and the other arm of the lever V is connected by a link-rod, W , at w with the connecting-rod K . (See Figs. 1 and 2.) With this construction, it will be seen that by shifting the lever U to set the block K' of the rod K at either end of the slot in link N' , or in intermediate positions each side of the link-center, the rod T will at the same time be moved to set the block P' and its pin P , so that as the engine is speeded fast or slow the pin P will be carried farther from or nearer to the point o^2 of plate O , for giving more or less motion to the valves while admitting steam at both sides of the piston, and cause the exhaust to open earlier or later, to avoid excessive back-pressure on the piston. It will, however, be understood that separate levers or other means for shifting the link-block K and the pin-block P independently of each other may be employed.

I now will describe the operation of the valve-motion with special reference to Figs. 1, 4, and 5 of the drawings.

In Fig. 1 the block K is secured at the upper end of the slot of link N' , so that the oscillation of the cylinder B will work the valves to give backward rotation to the engine-crank and fly-wheel in direction of the arrow x , and the lever U is set over to give full speed and power to the engine. When the crank M stands about vertically either above or below the shaft M' , the pin P of block P' will be in the slot n^2 of rock-plate N , and when the crank takes about horizontal positions to the right and left of the shaft M' the pin P will have reached its extremes of travel backward in the opposite guideways, $n^3\ n^4$, of plate N , and whichever way the crank may be turning. We will suppose the crank M stands in the lower vertical position indicated by dotted lines m' , Fig. 1. The piston then will be at half-stroke, with the cylinder inclining downward toward the crank, and the pin P , having just moved forward through the lower way, n^4 , of plate N , has escaped from the point o^2 of plate O into the slot n^2 , and the valves $H\ I$ have their maximum opening to admit live steam past valve H and to exhaust at valve I , and as the pin P had passed the point o^2 of the plate O , which then stands at the upward incline, the spring R had acted to swing the plate O to carry its point against the lower flange, n' , of plate N , so that as the crank moves forward toward the dotted position m^2 the pin P will leave slot n^2 and enter the upper guideway, n^3 , and the pin will continue to move back in way n^3 and swing the plates $N\ O$ downward, the pin reaching its maximum backward movement when the crank reaches the dotted position m^2 and the forward stroke of the piston is completed, and as the crank rises toward the dotted vertical position m^3 in Fig. 1 and the like position in full lines in Fig. 4 the pin P will gradually withdraw from the way n^3 , and will again pass the point o of plate O and enter the slot n^2 , and move forward a little in the slot until the crank reaches the position m^3 , which has caused the valve I to open to admit steam as the piston begins its back-stroke, the point o^2 of plate O then inclining downward, and the plate O has been swung by spring R so its point o^2 closes the upper guideway, n^3 , and while the crank approaches the dotted horizontal position m^4 , Fig. 1, the pin P will leave the slot n^2 and enter the lower guideway, n^4 , and will reach its maximum backward movement in said slot, and live steam will again be admitted past valve H , and the engine will exhaust at valve I as the piston completes its back-stroke, so as to drive the piston forward again, and as the crank M' continues its movement toward the lower vertical position, m' , the pin P will move forward from guideway n^4 into the slot n^2 , and full opening of valves $H\ I$ is secured, as before described.

To reverse the engine, it only is necessary

to shift the block K to the other side of the center of link N', when the valves will be operated in reverse of the movements above described.

It will be seen that by shifting the pin-block P' along on slot q closer to the trunnions of the cylinder the valves will have less movement imparted to them by the pin P, and by shifting block P' away from the trunnions the valves will have greater movement, so that the extent of port-openings or lap and lead of the valves may be governed closely for faster or slower movement in either direction and to insure economical use of the steam.

By the use of my improvement eccentrics for working the valves are dispensed with, and complication avoided in the construction and adjustment of parts of the valve-motion.

It is evident that the valve-operating mechanism, consisting of the rocking plates N O, link N', spring R, or its equivalent, and the arm Q, pin P, block K', and rod K, will operate equally well if arranged at the other end of the oscillating steam-cylinder B, and the rod K may also be connected to the ordinary slide-valves fitted to the ports of the cylinder, instead of to the rocking valves shown and above described; hence I make special claim to the valve-motion itself, as hereinafter set forth.

Having thus described my invention, what I claim as new, and desire to secure by Letters Patent, is—

1. The combination, in an oscillating engine, and with its cylinder, piston, piston-rod, crank, and crank-shaft, and rotary valves H I, seated at opposite ends of the steam-cylinder, and steam and exhaust ports, connecting opposite end cylinder-ports through the agency of the valves, substantially as specified, of arms H' I', fixed to the valves H I, respectively, a bar, J, connecting arms H' I', an angular rocking plate, N, having a link, N', a block, K', fitted in the link-slot, and adapted to be moved therein, a rod, K, connecting the block K' to the bar J and the valve-arms H' I', a rocking plate, O, hung on the pivot of the link-plate N, and having opposite angular edges, o o', converging at o², and said plate N having flanges n n', forming, with the edges of the plate O, the opposite guideways, n³ n⁴, and the slot n² in front of the end o² of plate O, a spring, R, or equivalent means for shifting the plate O so its point o² opens ways n³ n⁴ alternately, and a block, P', having a pin, P, adapted to enter and work in the guideways and slot n³ n⁴ n², and said block P' fitted adjustably in an arm, Q, fixed to the engine-

cylinder, to give motion to the valves, substantially as herein set forth. 60

2. A valve-motion for oscillating engines, comprising angular plates N O, fitted to rock on the same center, said plate N being provided with a link, N', and edge flanges, n n', and said plate O having side edges, o o', converging at o², and forming, with flanges n n' of plate N, the guideways and slots n³ n⁴ n², in which may work a pin connected with an arm fixed to the engine-cylinder, and the link N' of plate N carrying an adjustable block, K', adapted for connection to the cylinder-valves, to impart motion to them, and a spring, R, substantially as herein set forth. 65 70

3. The combination, in an oscillating engine, and with its cylinder, piston, piston-rod, crank, and crank-shaft, and the rotary valves H I, controlling opposite ports of the cylinder, substantially as specified, of the valve-arms H' I', bar J, rocking link and guide-plates N O, block K', rod K, spring R, and a block, P', having a pin, P, and fitted to an arm, Q, fixed to the oscillating cylinder B, and the starting and stopping lever U, connected for shifting the block K' in the link-plate N to either side of the center of the link, substantially as herein set forth. 75 80 85

4. The combination, in an oscillating engine, and with its cylinder, piston, piston-rod, crank, and crank-shaft, and the rotary valves H I, controlling opposite ports of the cylinder, substantially as specified, of the valve-arms H' I', bar J, rocking link and guide-plates N O, block K', rod K, spring R, block P', having pin P, and fitted to slide in an arm, Q, fixed to the engine-cylinder, the starting and stopping lever U, connected to rod K, for shifting the block K', and said lever U also connected to the block P', so that the pin P shall be shifted to and from the trunnions of the cylinder simultaneously with the shifting of the block K' in the link N' of plate N, substantially as herein set forth. 90 95 100

5. The engine-cylinder B, constructed with a bore for the piston and ports B' B², and with hollow trunnions C D and steam-passages C' D', and a steam-chest, F, provided with separate steam-chambers C' D', communicating with ports B' B², and rotary valves H I, fitted in seats over ports B' B², and cut away at the side, to open and close said ports alternately, substantially as herein set forth. 105 110
